HEAT TREATING APPARATUS

Homer W. Jones, Westfield, N. J., assignor to The
Linde Air Products Company, a corporation of
Ohio

Application May 1, 1940, Serial No. 332,648

13 Claims. (Cl. 266—4)

This invention relates to the heat treatment of metal bodies having a plurality of integral portions of the same longitudinal extent, or a plurality of laterally extending portions, and more particularly to the heat treatment of cams upon a camshaft. This invention also relates to apparatus for hardening in succession selected surface portions of a plurality of cams upon a camshaft, in which the surface portions to be hardened are heated by a source of localized high temperature heat, such as an oxy-acetylene blowpipe flame.

Cams are generally used to lift or actuate cam followers, and each cam upon a camshaft is usually adapted to actuate a follower only once during each rotation of the camshaft. Consequently, the greater part of the surface of each cam normally is cylindrical and a laterally extending portion, usually substantially triangular in cross-section, is disposed at the point at which the cam follower is lifted or actuated. Since the greatest wear will occur on this laterally extending portion, which also may be termed the "apex," it is usually necessary to harden only the surface of the apex. Of course, when desired, a greater portion of the surface of each cam may be hardened.

The various physical dimensions of camshafts, such as overall length, distance between cams, cam widths, and cam ramp contours, tend to vary widely. Consequently, apparatus for successfully hardening at least the laterally extending portions or apices of cams must necessarily be so constructed that the least possible time will be required to align a laterally extending portion of a cam being treated with the heating means, or to make adjustments for cam spacing and other variables.

The objects of this invention are to provide apparatus for heat treating in succession a plurality of laterally extending portions of a metal body; to provide apparatus for hardening a cam or a plurality of cams on a camshaft whereby each cam is hardened individually, and by which the results of hardening may be uniformly duplicated in the case of all cams upon the camshaft; to provide such apparatus which is easily adjustable to permit treatment of camshafts of varying lengths and cams of different widths; to provide such apparatus by which a relative reciprocal motion between a cam being treated and a source of high temperature heat may be effected; to provide such apparatus wherein high temperature heating flames are directed from a blowpipe against the surface portions to be hardened, and wherein the blowpipe may be moved away from the cam being treated and simultaneously therewith the supply of gases to the blowpipe automatically turned off; to provide such apparatus wherein

the laterally extending portion of each cam may be registered in operative relation with respect to a single blowpipe head; and, generally, to provide such apparatus which will be simple in construction and economical in operation.

Other objects and novel features of this invention will become apparent from the following description and accompanying drawing, in which:

Fig. 1 is a side elevation, partially in section, of apparatus, constructed in accordance with this invention, for hardening in succession a plurality of cams upon a camshaft;

Fig. 2 is a horizontal sectional view of the apparatus of Fig. 1, looking downwardly along line 2—2 of Fig. 1; and

Fig. 3 is a fragmentary vertical view, illustrating the attachment of motor-operated means for reciprocating the blowpipe of the apparatus of Fig. 1.

In accordance with this invention, apparatus for hardening in succession selected surface portions of a plurality of cams on a camshaft may comprise, in general, a support S for a camshaft A having cams C; a blowpipe B for heating in succession the apex of each cam; a registering device R for aligning cams and placing them in proper position for heating; and a tank T, containing quenching fluid Q. As soon as the surface of the apex of a cam has been heated, the blowpipe B may be withdrawn in a horizontal direction, the heating gases automatically turned off by a valve V which controls the flow of heating gases to blowpipe B, and support S moved downwardly by a handwheel H, the cam and its heated apex thus being lowered into quenching fluid Q. A second cam is thereby moved into position for heating, and the registering device R is utilized in placing the apex of this second cam in proper alignment for heating when blowpipe B is once again moved into heating position.

The blowpipe B preferably directs heating flames over only a part of the width of the apex of each cam in order to accommodate the narrowest width of cam which may be treated. So that the entire width of each apex will be heated, and also to produce a more uniform heating effect, the blowpipe B preferably is reciprocated longitudinally of the camshaft during heating. The blowpipe B is reciprocated longitudinally of the camshaft an amount sufficient so that the upper and lower edges of each apex will not be directly heated but will be heated primarily by conduction from the portions directly heated. This compensates for the tendency for a greater amount of heat to be conducted away from the central portion, and prevents the edges from becoming overheated. This reciprocation or oscillation may be effected man-

ually, or, as illustrated in Fig. 3, by means of a motor M.

As in Figs. 1 and 2, the support S for cam-shaft A includes a vertically-disposed column or I-beam 10 having an arm 11 extending from its lower end, arm 11 being provided with a lower center 12 which engages the center hole in the lower end of camshaft A. An upper arm 14, adjustable upwardly and downwardly along the front flange of column 10, is secured to the flange by a clamping screw 15 and is provided with a movable upper center 16 which engages the center hole at the upper end of camshaft A. Upper center 16 threadedly engages arm 14, and the vertical position of center 16 may be adjusted by a handle 17. Column 10 preferably is of sufficient length so that the longest camshaft to be treated may be placed between centers 12 and 16 by properly positioning upper arm 14, upper center 16 being moved toward or away from the end of a camshaft in replacing a treated camshaft by an untreated one, or placing an untreated camshaft in the support. Also, tank T preferably corresponds in depth to the length of column 10, and is embedded in a foundation 18 so that blowpipe B and registering means R will be more accessible to an operator. If desired, tank T may be located in a relatively higher position with respect to the floor or foundation, and a suitable platform upon which an operator 30 may stand provided.

Column 10, during upward and downward movement, is guided by rollers 20 engaging the rear flange thereof. Rollers 20 are journalled on suitable stub-shafts mounted in vertical plates 21, which are secured to tank T at the rear in any suitable manner, such as by welding. Journalled in the upper end of plates 21 is a shaft 22, to the free or outboard end of which hand-wheel H is keyed. A sprocket 23, disposed between plates 21, is also keyed to shaft 22, and a chain 24 passes over sprocket 23. One end of chain 24 is attached to the bottom of column 10 and the other end is attached to a series of weights 25 which are disposed in a well 26 sunk in foundation 18.

Weights 25, which balance the weight of support S and camshaft A, are removable, a slightly greater number of weights than just sufficient to counterbalance the weight of the support and the camshaft preferably being used to prevent lowering when a camshaft is loaded into the machine. This additional weight, of course, will be compensated for as the camshaft moves into the quenching liquid and the liquid exerts a buoying effect on column 10 and the camshaft.

To provide a braking action when handwheel H is turned, and to prevent the camshaft from moving downwardly during heating due to jar-ring of the apparatus or other causes, a bolt 27 may be turned to bear against the rear flange of column 10. Bolt 27 is mounted on, and threadedly engages, a bracket 28 extending forwardly from one of plates 21.

As in Fig. 2, the registering device R includes a lever 31 pivoted on a pin 32 which is mounted on a bracket 33, in turn attached to the side of tank T opposite column 10. An indexing plate 34 is secured to one end of lever 31 and is adapted to engage the apex of a cam to register or align the same in proper position for heating by blowpipe B. With blowpipe B withdrawn to the dotted position of Fig. 2, lever 31 is swung about pin 32 and the camshaft turned about its axis so that the apex of the cam to be treated will fit exactly

10 into a V notch in indexing plate 34. The V notch in indexing plate 34, of course, corresponds in shape to the apices of the cams of the particular camshaft being treated, and plate 34 may be replaced by other indexing plates having suitable V notches when cams having different configuration are to be treated. The indexing plate 34 may be made of a relatively thin piece of metal, thus being cheaply produced and inexpensive to carry in stock in large numbers.

The support for blowpipe B comprises an arm 36 provided with a hinged joint 37 so that the outer end of arm 36 may be moved upwardly and downwardly with respect to its inner end. 15 The inner end of arm 36 is pivoted on a pin 38 extending from a bracket 39 attached to the side of tank T adjacent plate 21. The blowpipe B is secured to the outer end of arm 36 by a clamp 40 which may be tightened by a set screw 41 to secure the blowpipe in any desired radial or longitudinal position.

As blowpipe B moves from the heating position (shown in full lines in Fig. 2) to the registering position (shown in dotted lines in Fig. 2), or vice versa, the outer end of arm 36 will be supported by a slide 43, secured to rim 44 of tank T in any suitable manner, such as by welding. Slide 43 extends outwardly from the tank a distance sufficient to permit the blowpipe to be moved far enough away from the camshaft to prevent interference with the registering device R during use of the latter. The outer end of slide 43 is provided with a flange 45 which acts as a stop for arm 36 when the blowpipe is in the registering or dotted position of Fig. 2. The inner end of slide 43 is provided with a similar flange 46, which, however, is provided with a threaded aperture cooperating with a positioning bolt 47 secured in any desired position by a nut 48. Bolt 47 acts as an adjustable stop for blowpipe supporting arm 36, to space blowpipe B the proper distance from the cam apex during heating.

A combustion-supporting gas, such as oxygen, and a combustible gas, such as acetylene, are supplied to blowpipe B by hoses 50 and 51, respectively, which lead from gas-control valve V. Gas-control valve V is mounted on a bracket 52 secured to the side of tank T and is provided with inlet connections 53 on the under side thereof to which oxygen and acetylene may be led from suitable sources of supply thereof. Control of the flow of gases through valve V is effected by spring-loaded push buttons 55, i. e. depression of push buttons 55 causes the flow of heating gases to blowpipe B to be initiated, and release of the pressure permits buttons 55 to spring outwardly and the flow of heating gases to be discontinued.

60 Blowpipe supporting arm 36 is provided with suitable means cooperating with push buttons 55 so that the heating gases will be turned on when blowpipe B is moved into heating position, and turned off when the blowpipe is moved into registering or dotted position of Fig. 2. For this purpose, an extension 56, formed integrally with or secured to the end of arm 36, is provided with adjustable pins or bolts 57 which actuate push buttons 55. The position of each of bolts 57 is preferably so adjusted that the oxygen will be shut off prior to the acetylene, to prevent pure oxygen from passing through blowpipe B and attacking the heated surface at the termination of heating.

65 Blowpipe B includes a body 59 provided with valves 60 for controlling the flow of oxygen and

acetylene to a suitable mixer installed within body 59. A fork 61 conveys the combustible mixture to two heads or tips 62 which are provided with suitable outlets for discharging the combustible mixture, to form heating flames which are directed against the surface of the apex of the cams being heated. The outlets of each head 62 are preferably disposed in transverse parallel rows but placed closer together at one end of each row than at the other end, or disposed in any other suitable manner, whereby more heat will be applied adjacent the thicker portion of the apex than adjacent the point of the apex. This compensates for the tendency for a greater amount of heat to be conducted into the thicker portion of the apex than to the point. A pilot light tube 63, supplied with an air-acetylene or air-city gas mixture, provides a small flame which ignites the combustible mixture issuing from the outlets in heads 62 when the heating gases are turned on. The pilot flame is preferably left burning during the entire operation, being of insufficient intensity to heat to an appreciable extent the surfaces being treated.

Quenching fluid is supplied to tank T by an inlet pipe 65 which extends downwardly to a point adjacent the bottom of tank T, the flow through pipe 65 being controlled by a valve 66. Valve 66 is preferably left open or slightly open at all times to provide a continuous flow of quenching fluid through the tank, so that fresh, cool quenching fluid will continually rise to the top of the tank. To maintain the level of liquid within the tank accurately, and to draw off heated quenching liquid, a drain or overflow pipe 67 extends upwardly within tank T to a point just below the top of the tank. Warmed cooling liquid overflowing into pipe 67 is removed through a fitting 68, into which pipe 67 is screwed and which is welded or otherwise suitably secured to the bottom of tank T in a liquid-tight manner. As water normally is used as a quenching fluid, fitting 68 normally may be connected with a drain or sewer. However, in case special quenching solutions, such as an aqueous solution of sodium hydroxide, are used, fitting 68 is preferably connected with a suitable pump and cooling coil, if necessary, (not shown) which will return the quenching medium to inlet pipe 65. In either event, a continuous circulation of quenching fluid through tank T is assured.

Further to assure that the quenching liquid at the top of tank T will be sufficiently cool to effect adequate quenching of the heated surface of each cam apex as it is lowered into the same, a baffle 69 is disposed at the surface of the quenching medium. Baffle 69 is formed of suitable insulating material, such as "Transite board," and is provided with a central aperture 70, sufficiently large to permit the cams to pass through. The baffle is supported by a plurality of bracket strips 71, bolted or otherwise suitably secured both to the baffle and to the rim of tank T. When a cam-shaft to be treated is placed between centers 12 and 16, column 18 is raised sufficiently so that lower center 12 is at or slightly above the water level, but not sufficiently so that lower supporting arm 11 will strike baffle 69.

For mechanically oscillating blowpipe B, a motor M, as in Fig. 3, may be secured to the side of tank T by a strap 72. Motor M may be a slow-speed motor, or a higher speed motor provided with an integral speed-reducer. An oscillating cam 73 is mounted on the end of motor shaft 74 and engages the lower leg of a Z-shaped cam fol-

lower 75, which may be secured to the outer pivoted portion of arm 36 in any suitable manner, such as by welding.

Rotation of oscillating cam 73 causes blowpipe support 36 to be reciprocated between suitable limits, as indicated by the full and dotted positions of Fig. 3, although the amplitude of oscillation is exaggerated for the sake of clarity. Since the length of the outer or pivoted portion 10 of arm 36 is a large multiple of the amplitude of oscillation, no particular difficulty will be encountered because heads 62 oscillate in a small segment of an arc, because this segment is substantially a straight line, and the heads will at all times remain at proper distances from the surfaces being heated.

When a different amplitude of oscillation is desired, due to a greater cam width on the cam-shaft being treated, oscillating cam 73 may be replaced by another oscillating cam having the desired contour. Oscillating cam 73 is preferably made of relatively cheap material, as is indexing plate 34, so that no great expense will be involved in providing different oscillating cams for different widths of cams to be treated.

If more nearly complete automatic operation is desired, a suitable switch for motor M may be positioned at or adjacent adjustable stop 47, so that when the blowpipe head is moved into heating position, arm 36 will actuate the switch and motor M will be started automatically.

The complete operation of the apparatus just described is as follows:

Assuming the support S to be in the vertical position of Fig. 1, to place the first of a series of similar camshafts to be treated in the machine, the number of weights 25 is adjusted or brake bolt 27 screwed inwardly so that the support will not lower when the camshaft is loaded into the machine. Next, clamp 15 is loosened, upper arm 14 moved upwardly, and the lower end of the camshaft placed upon lower center 12. Then upper arm 14 is lowered until center 16, when screwed downwardly, will engage the center hole in the upper end of the camshaft, and so that a camshaft can be replaced without resetting upper arm 14. Clamp 15 is tightened and upper center 16 screwed downwardly against the camshaft with sufficient pressure so that the camshaft will remain in any radial position, but can be turned easily. Weights 25 are then adjusted so that, when free, support S and the camshaft will tend to move slowly downwardly, and brake 27 adjusted so that a slight effort is required to raise or lower the camshaft. Wheel H is then turned so that the lowest cam is in approximate vertical position for treatment.

Registering device R is then swung into engagement with the cam to be treated and the camshaft turned or moved radially so that the cam is in proper radial position. The cam may also be moved vertically by means of wheel H to the proper vertical position, determined by aligning the top of the cam with the top of plate 34 or in any other suitable manner.

The constituents of the combustible mixture and the position of the blowpipe previously having been adjusted, pilot 63 is lighted and the blowpipe is swung inwardly until arm 36 strikes bolt 47, i. e. to the full position of Fig. 2. The heating gases are automatically turned on as pins 57 engage push buttons 55 of valve V, thus initiating heating. During heating, blowpipe B may be oscillated manually, or by means of motor

M and cam 73. The amplitude of oscillation is preferably such that the upper and lower edges of the cam apex will not be heated directly, and, as stated previously, the heating flames discharged from heads 62 are not directed against the point or tip of the cam apex.

At the expiration of the heating time, normally determined by trial, heating is discontinued by moving the blowpipe away to the dotted position of Fig. 2, thus turning off the heating gases. Simultaneously, the entire camshaft is lowered so that the heated cam apex will immediately be plunged into the quenching liquid, the upper portion of which remains cool due to the circulation of cooling medium and also due to the shielding effect of baffle 69. As the next cam to be treated will be substantially in the correct vertical position, the cam shaft is turned and the apex registered in correct radial and vertical alignment by registering device R, as previously described. The blowpipe B is then swung into heating position, the heating gases automatically turned on, and the operation proceeds as before.

After all of the apices have been hardened in this manner, the camshaft is moved upwardly by means of handwheel H, and the treated camshaft removed, upper center 16 being moved away from the camshaft for the purpose of replacing the treated camshaft by an untreated one. In case the remaining camshafts to be treated are identical with the first treated, the entire operation proceeds quickly and smoothly, as no further adjustments need be made. Furthermore, for differences in length of camshaft, in cam ramp contour, or in width of cam, the necessary adjustments of upper arm 14, and the replacement of plate 34 and/or oscillating cam 73, respectively, are easily and quickly made.

Since only a single cam, (a relatively small portion of the camshaft) is heated at a time, no particular difficulty will be encountered because of expansion or contraction of the camshaft during treatment. Furthermore, since the registering device insures that each cam apex will be placed in the same position with respect to the heating heads, and since each apex is preferably heated for the same length of time, uniform results will be obtained in the case of each cam and each camshaft treated. In addition, uniform cooling of each cam treated is insured by the continuous supply of cool quenching medium to the top quenching liquid Q.

From the foregoing, it will be apparent that this invention provides a relatively simple and inexpensive apparatus for uniformly duplicating results in treating a plurality of laterally extending portions of an elongated ferrous metal body. Although the treatment of cams upon a camshaft has been described with particularity, it will be evident that the apparatus is suitable for use in the treatment of other metal objects. Furthermore, various changes may be made in the apparatus without departing from the spirit and scope of this invention.

What is claimed is:

1. In apparatus for heat treating in succession a plurality of laterally extending portions of a metal body, such portions being spaced at different points circumferentially of said body, the combination of means supporting said body for radial movement; means for applying high temperature heat to the surface of a laterally extending portion of said body; means supporting said heating means for movement toward and

away from such laterally extending portion; means movable toward and away from said body for registering a laterally extending portion in operative position with respect to said heating means; and means constructed and arranged to effect an intermittent relative movement longitudinally of said body between said body and said heating means, whereby successive laterally extending portions of said body may be moved into operative position with respect to said heating means.

2. In apparatus for heat treating in succession a plurality of laterally extending portions of a metal body, such portions being spaced at different points circumferentially of said body, the combination of means supporting said body; means for applying high temperature heat to the surface of a laterally extending portion of said body; means supporting said heating means for movement toward and away from such laterally extending portion; means for registering such laterally extending portion in circumferentially operative position with respect to said heating means; means constructed and arranged to effect a relative movement longitudinally of said body between said body and said heating means, whereby successive laterally extending portions of said body may be moved into operative position with respect to said heating means; and means controlling the operation of said heating means, said supporting means and said controlling means being so constructed and arranged that heating is initiated when said heating means is moved toward said body and into heating position and heating is discontinued when said heating means is moved away from said body.

3. Apparatus for heat treating in succession a plurality of cams upon a camshaft comprising, in combination, means supporting said camshaft with the longitudinal axis thereof disposed vertically; means for applying high temperature heat to a surface portion of a cam; means supporting said heating means for horizontal movement toward and away from such cam; means constructed and arranged to effect a downward movement of said camshaft whereby successive cams may be placed in operative position with respect to said heating means; and means for cooling the heated surface of each cam after heating so as to harden the same.

4. Apparatus for heat treating in succession a plurality of cams upon a camshaft as defined in claim 3, which includes means for exerting a braking effect upon the vertical movement of said camshaft.

5. Apparatus for heat treating in succession the laterally extending portions of a plurality of cams upon a camshaft comprising, in combination, means supporting said camshaft for radial movement about its longitudinal axis and with the longitudinal axis of said camshaft disposed in a vertical position; means for directing high temperature heating flames against the surface of the laterally extending portion of a cam; means supporting said heating means for horizontal movement toward and away from such cam; means movable toward and away from said camshaft for registering the laterally extending portion of each cam in operative radial position with respect to said heating means; a body of quenching liquid disposed beneath said heating means; and means constructed and arranged to effect a vertical movement of said camshaft, whereby successive

laterally extending portions of said cams may be moved into operative vertical position with respect to said heating means, and each cam after heating may be lowered into said body of quenching liquid.

6. Apparatus for heat treating in succession the laterally extending portions of a plurality of cams upon a camshaft as defined in claim 5, which includes a baffle disposed beneath said heating means and directly above said quenching liquid, to minimize heating of said quenching liquid by said heating flames.

7. Apparatus for heat treating in succession a plurality of cams upon a camshaft comprising, in combination, means supporting said camshaft with its longitudinal axis disposed substantially vertically; a blowpipe for directing high temperature heating flames against a surface portion of a cam; means supporting said blowpipe for horizontal movement toward and away from such cam; means constructed and arranged to effect an intermittent vertical movement of said camshaft whereby successive cams may be placed in operative position with respect to said blowpipe; means for effecting a vertical oscillation of said blowpipe during heating; and means for cooling the heated surface portions of successive cams so as to harden the same.

8. Apparatus for heat treating in succession a plurality of cams upon a camshaft comprising, in combination, means supporting said camshaft with its longitudinal axis disposed substantially vertically; a blowpipe for directing high temperature heating flames against a surface portion of a cam; means supporting said blowpipe for horizontal movement toward and away from such cam, said means comprising an arm pivoted at one end for horizontal movement and hinged for vertical movement of the opposite end thereof; means constructed and arranged to effect a vertical movement of said camshaft whereby successive cams may be placed in operative position with respect to said blowpipe; means for effecting a vertical oscillation of said blowpipe during heating; and means for cooling the heated surface portions of successive cams so as to harden the same.

9. Apparatus for heat treating in succession a plurality of cams upon a camshaft as claimed in claim 8, in which said means for effecting a vertical oscillation of said blowpipe comprises means for reciprocating said opposite end of said blowpipe supporting arm.

10. Apparatus for heat treating in succession the laterally extending portions of a plurality of cams upon a camshaft, comprising, in combination, means for supporting said camshaft for radial movement about its longitudinal axis and with the longitudinal axis of said camshaft disposed in a vertical position; a blowpipe for directing high temperature heating flames against the surface of a laterally extending portion of a cam; means pivoted at a point on one side of said camshaft and supporting said blowpipe for horizontal movement toward and away from such cam; means pivoted at a point substantially opposite said first-mentioned point with respect to said camshaft, and horizontally movable toward and away from said camshaft, for registering the laterally extending portion of such cam in operative radial position with re-

spect to said heating means; means constructed and arranged to effect a vertical movement of said camshaft, whereby the laterally extending portions of successive cams may be moved into operative vertical position with respect to said blowpipe; and means for cooling the heated surface portion of successive cams so as to harden the same.

11. Apparatus for heat treating in succession the laterally extending portions of a plurality of cams upon a camshaft as defined in claim 10, which includes means for supplying said blowpipe with a combustible gas and a combustion-supporting gas; a valve for controlling the flow of such gases to said blowpipe; and means attached to said blowpipe supporting means for operating said valve, so as to initiate the flow of such gases to said blowpipe when said blowpipe is moved toward a cam to be treated and into heating position, and to discontinue the flow of such gases when said blowpipe is moved away from such cam.

12. Apparatus for heat treating in succession the laterally extending portions of a plurality of cams upon a camshaft as defined in claim 10, in which said cooling means comprises a tank of quenching liquid disposed beneath said blowpipe and into which a heated cam is lowered, such apparatus also including an inlet discharging cooling medium into said tank in the lower portion thereof, and an outlet pipe having an open upper end disposed a relatively short distance below said blowpipe for removing heated quenching liquid and maintaining constant the level of quenching liquid in said tank.

13. Apparatus for heat treating in succession the laterally extending portions of a plurality of cams upon a camshaft, comprising, in combination, means for supporting said camshaft; a blowpipe for directing high temperature heating flames against the surface of a laterally extending portion of a cam; means supporting said blowpipe for pivotal movement toward and away from such cam substantially in a plane which is substantially perpendicular to the longitudinal axis of said camshaft; means mounted for pivotal movement toward and away from said camshaft, for registering the laterally extending portion of a cam in operative radial position with respect to said heating means, said registering means also being movable substantially in a plane which is substantially perpendicular to the longitudinal axis of said camshaft; means constructed and arranged to effect a relative movement between said camshaft and said supporting means in the direction of the longitudinal axis of said camshaft, whereby the laterally extending portions of successive cams may be made to coincide with the plane of movement of said blowpipe; means for effecting a radial movement of said camshaft, whereby each cam may be moved into operative radial position with respect to said blowpipe through said registering means and said registering means may then be pivoted out of the way to permit said blowpipe to be moved into heating position with respect to the laterally extending portion so registered; and means for cooling the heated surface portions of successive cams so as to harden the same.

HOMER W. JONES.
